UNITED STATES PATENT OFFICE.

ANTON A. LERAAS, OF SPOKANE, WASHINGTON.

BRUSH.

Application filed May 18, 1925. Serial No. 31,036.

To all whom it may concern:

Be it known that I, ANTON A. LERAAS, a citizen of the United States, residing at Spokane, in Spokane County and State 5 of Washington, have invented certain new and useful Improvements in Brushes, of which the following is a specification.

My present invention relates to improvements in brushes of the fountain type and 10 adapted especially for use in cleaning or scrubbing windows, washing down building walls, and other similar surfaces where a constant and profuse supply of water or cleansing liquid is required for the brushing or scrubbing operation.

The primary object of the invention is the provision of a device of this type adapted for manual operation which is simple in construction and involves the use 20 of a minimum number of parts thus rendering it possible for inexpensive manufacture and eliminating likelihood of disarrangement of parts. The several parts of the device are readily detachable to permit facile 25 separation and compact arrangement of the parts for storage when not in use, and the parts may with facility be assembled for use when required. Means are provided for preventing leakage of water or waste of 30 the cleansing liquid and other features of merit are present in the device to enhance its efficiency and manipulation, as will hereinafter be more fully set forth and claimed.

35 The invention consists in certain novel combinations and arrangements of parts as illustrated in the accompanying drawings where I have shown one complete embodiment of my invention with the parts combined and arranged according to the best mode I have thus far devised for the practical application of the principles of my invention.

Figure 1 is a plan view showing a brush 40 and its connections embodying my invention.

Figure 2 is an enlarged view of the device in side elevation with parts in section for convenience of illustration.

50 Figure 3 is an enlarged plan view showing the locking means of the brush head.

Figure 4 is a detail sectional view of the head structure and showing the locking means for the head and handle.

55 In carrying out my invention I utilize a head 1 of wood or other suitable material

in the form of a flat disk with rounded edge, and an annular, exterior guard ring 2 of rubber or other cushioning material is secured around the exterior central periphery 60 of the head.

Any suitable type of bristles are used in the form of tufts 3 for the brush and they are secured in the head in approved manner to insure durability and efficiency in the 65 operation of the brush.

The head is provided with a transverse opening or bore 4 centrally thereof in which a sleeve or tubular member 5 is secured, said sleeve having a closed bottom with lateral perforations 6 for exit of water or other cleansing liquid from the sleeve, and the upper end of the sleeve is fashioned 70 with an annular seat 5' that projects above the rear or upper face of the head. 75

At the lower or front face of the head the sleeve is secured therein by means of a flanged bushing 7 that encases the sleeve and is fixed to the head in the lower end of the bore 4. At the rear or top face of 80 the head a second bushing 8 is secured in the bore and embraces the sleeve 5. This bushing 8 has a flat head plate 9 which is secured to the head by means of screws 10, and on the face of this plate is arranged 85 a pair of opposed integral locking flanges 11 which are of arcuate shape and spaced at diametrically opposite sides of the axis of the sleeve 5.

The tubular handle 12, by means of which the device is manipulated is of suitable length for this purpose, and its lower bent end is fashioned with a reduced collar 12' that fits neatly into the annular seat 5' of the sleeve 5 as indicated in Figure 4, to center 95 the handle in the head when the parts are being assembled and to retain the handle and sleeve in close alinement when the parts are assembled, the joint between the parts making a substantial continuation of the 100 hollow handle for supplying water or other liquid cleanser from the handle through the sleeve of the head and thus to the tufts or bristles of the brush.

For locking the handle to the head I employ a pair of opposed diametrically arranged, arcuate flanges 13 projecting laterally from the handle for co-action with the overhanging flanges 11 of the head plate 9. To insure a leak-proof joint between 105 these parts an annular gasket or packing ring 14 is carried by the head under 110

the flanges 13 of the handle, to prevent leakage of water from the joint between the handle and sleeve. It will be apparent that the head may be applied to the handle, or the handle applied to the head with the pairs of complementary locking flanges disposed at right angles. Then by a quarter turn of one of said members with relation to the other the pairs of complementary locking flanges are frictionally engaged to securely clamp the head on the handle.

To further secure the handle and head against displacement or relative movement while the device is in use I utilize a set screw or bolt 15 carried in one of the flanges 11 of the head plate 9 and threaded through an opening in said plate for engagement with one of the flanges 13 which may have a depression or socket in its face as indicated at 15' for the reception of the end of the set screw or bolt.

The water or liquid cleanser is supplied to the device through a flexible pipe or hose 16 and a coupling nut 17 is employed to detachably connect the hose with the handle.

It will be apparent that the several parts may be detached with facility, when not required for use, by loosening the nut 17 to disengage the handle from the hose, and the head may be disengaged from the handle by first loosening the set screw or lock bolt 15, and then giving the handle or the head a quarter turn to disengage the locking flanges. The sleeve 5 is rigidly held in position at all times in the head by means of the bushings 7 and 8.

Having thus fully described my invention, what I claim is new and desire to secure by Letters Patent is—

1. The combination with a brush head 40 having a distributing sleeve therein, of a locking bushing having a head plate and a pair of opposed, arcuate, overhanging flanges on said plate, a tubular handle having a pair of complementary flanges for 45 frictional co-action with the plate-fingers, and a set bolt for said complementary flanges.

2. The combination with a brush head having a distributing sleeve formed with an 50 annular seat, of a bushing surrounding said sleeve and provided with a head-plate, a pair of opposed overhanging arcuate flanges on said plate, a tubular handle having a collar to fit said seat, and a pair of complementary flanges on said tubular handle for frictional co-action with said overhanging flanges.

3. The combination with a brush head having a distributing sleeve formed with an 60 annular seat, of a bushing surrounding said sleeve and provided with a head plate, a pair of opposed overhanging arcuate flanges on said plate, a tubular handle having a 65 collar to fit said seat, a pair of complementary flanges on said handle for co-action with the plate-flanges, and a set bolt in a plate-flange for co-action with one of the handle-flanges.

In testimony whereof I affix my signature.

ANTON A. LERAAS.
